UNITED STATES PATENT OFFICE

2,201,841

IRONING MACHINE

George W. Wardwell, Jr., Nichols, Conn., assignor to General Electric Company, a corporation of New York

Application August 13, 1936, Serial No. 95,835

5 Claims. (Cl. 38—66)

The present invention relates to ironing machines of the type in which ironing is effected between a heated shoe and a co-operating pressing member.

5 In ironing machines of this type there is a considerable heat loss from the heated shoe when the shoe is out of engagement with the co-operating pressing member.

The object of my invention is to provide an 10 improved construction which will decrease the heat loss of the shoe, and for a consideration of what I believe to be novel and my invention attention is directed to the accompanying description and the claims appended thereto.

15 In the accompanying drawing, Fig. 1 is an end elevation of an ironing press equipped with a shoe embodying my invention, and Fig. 2 is a fragmentary end elevation of the shoe.

I have shown my invention as applied to an 20 ironing press of the type shown in my application Serial No. 750,620, filed October 30, 1934, now Patent No. 2,135,266. In this construction the pressure developing mechanism is contained within a cylinder 1 having a flange 2 for supporting the cylinder on the top 3 of a table. Within the cylinder is a piston on the top of which is mounted a suitably padded buck 4. On the lower end of the cylinder is pivoted a carriage 5 having an arm 6 which supports a suitably 25 heated shoe 7. The shoe is moved into and out of register with the buck by means of a handle 8 attached to the front end of the shoe. The rearward movement of the carriage is cushioned by a spring 9 connected to toggle links 10 and 11 which are respectively pivoted to the cylinder and to the carriage.

30 When the shoe is in the out-of-register position shown in dotted lines in Fig. 1 the shoe is inclined to the horizontal, and with shoes of the conventional construction there would be a considerable heat loss due to convection currents flowing upward along the heated face of the shoe.

In the present construction this heat loss is 45 decreased by a metal plate 12 having flanges 13 which telescope over the heated face 14 of the shoe and are slidably mounted thereon by pin and slot connections 15. With this construction the plate is normally biased by gravity to the 50 position shown in Fig. 2 in which it is spaced from the heated surface of the shoe and in which the flanges 13 prevent convection currents flowing along the heated face of the shoe. If the flanges 13 were omitted, these convection currents would still be substantially decreased due

5 to the close spacing of the plate 12 and the shoe. This construction provides a dead air space between the plate 12 and the heated face of the shoe which insulates the plate from the shoe. There is, therefore, less heat loss due to 10 the convection currents which flow along the outer surface of the plate 12. When the shoe is pressed against the buck the plate 12 is moved into contact with the face 14 of the shoe and is quickly heated thereby. The outer surface of 15 the plate 12 then forms the work contacting surface of the shoe. Since the face 14 of the shoe does not come in contact with the work, it need not be polished and may be a low quality casting having a rough or porous surface. If the outer 20 surface of the plate 12 becomes damaged so that it is no longer suitable for ironing, it may be easily replaced. This is a decided advantage over shoe constructions in which the ironing surface is integral with the shoe casting. Another 25 advantage of this construction is that the plate 12 may be removed from the shoe when it becomes necessary to clean its ironing surface. When the ironing pressure is released the plate 12 returns by gravity to the position shown in Fig. 2 in which it forms an effective insulator for the face of the shoe. This construction results in a substantial decrease in the heat loss of the shoe.

35 What I claim as new and desire to secure by Letters Patent of the United States, is:

1. In an ironing machine, a heated shoe having a face adapted to be pressed against a co-operating pressing member, a metal plate covering said face of the shoe, means for supporting 35 the plate whereby the plate is normally spaced from the face of the shoe and whereby the plate is moved into contact with the face of the shoe when the shoe is pressed against a cooperating pressing member, and means for preventing convection currents between said plate and said shoe when the plate is in its normal position.

2. In an ironing machine, a heated shoe having a face adapted to be pressed against a co-operating pressing member, a metal plate covering said face of the shoe, means for supporting the plate whereby the plate is normally spaced from the face of the shoe and whereby the plate is moved into contact with the face of the shoe when the shoe is pressed against a cooperating 40 pressing member, and flanges on the plate telescoping over said face for preventing convection currents between said plate and the shoe when the plate is in its normal position.

3. In an ironing machine, a heated shoe hav- 55

- ing a lower face adapted to be pressed against a cooperating pressing member, a metal plate covering said face of the shoe, pin and slot connections supporting the plate whereby the plate is normally spaced from the face of the shoe and whereby the plate is moved into contact with the face of the shoe when the shoe is pressed against a cooperating pressing member, and means for preventing convection currents between said plate and said shoe when the plate is in its normal position.
5. In an ironing machine, an ironing element on which the material to be ironed is arranged, a cooperating ironing element comprising a heated shoe having a heated face adapted to cooperate with said first ironing element, means for effecting relative movement of said ironing elements 10 into and out of register whereby material may be arranged on said first ironing element when the elements are out of register, means for effecting pressing engagement of the ironing elements when in the in-register position, thermal insulating means on the heated face of the shoe for decreasing the heat transfer from said heated face, and means for rendering said thermal insulating means ineffective when the ironing elements are in pressing engagement. 15
4. In an ironing machine, a heated shoe having a face adapted to be pressed against a cooperating pressing member, means for supporting said shoe whereby the face of the shoe is inclined to the horizontal when out of engagement with the cooperating pressing member, a metal plate covering said face of the shoe, means for supporting the plate whereby the plate is normally spaced from the face of the shoe and whereby the plate is moved into contact with the face of the shoe when the shoe is pressed against 20
